EUGENE L. SANBORN, OF MILWAUKEE, WISCONSIN, ASSIGNOR TO SMITH ENGINEERING WORKS, OF MILWAUKEE, WISCONSIN, A CORPORATION OF WISCONSIN.

CRUSHING-MACHINE.

1,309,104.

Specification of Letters Patent.

Patented July 8, 1919.

Application filed November 14, 1917. Serial No. 202,037.

To all whom it may concern:

Be it known that I, EUGENE L. SANBORN, a citizen of the United States, residing at Milwaukee, in the county of Milwaukee and 5 State of Wisconsin, have invented a certain new and useful Improvement in Crushing-Machines, of which the following is a specification.

My invention relates to improvements in 10 gyratory crushers and has for one object to simplify the gyratory crusher. Another object is to provide means whereby the position of the crushing head in the hopper may be adjusted with a minimum of difficulty 15 in order to compensate for wear or change of adjustment. Another object is to provide a crushing machine wherein there will be a minimum number of places where clearance must be left in the line of crushing pressure. 20 In the past it has been proposed to use a crushing machine of general type wherein the rotating eccentric sleeve was surrounded by a cylindrical sleeve and wherein the crushing head is slidably mounted upon the 25 cylindrical sleeve. In order that the crushing head may move longitudinally along the sleeve clearance must be left. Experience shows that when you use a type of machine wherein there are a number of loose 30 fits in direct line with the crushing pressure a pounding or hammering will develop which results in battering or peening the head liner which thus wears larger than the bore. The result is that the pound gets 35 worse and before long the whole bearing is battered to pieces. By eliminating one of the loose fits this pounding is minimized.

In my device I make the cylindrical sleeve and the crushing head integral thus doing 40 away with the clearance and stiffening the parts without increase in weight. I protect the eccentric sleeve by carrying an integral extension down from the crushing head into the oiling chamber and putting the crushing 45 head into engagement with the eccentric sleeve only throughout an intermediate part of its length so that there is room for upward or downward adjustment of the crushing head with respect to the eccentric sleeve 50 without decreasing the bearing surface off sleeve or head.

My invention is illustrated more or less diagrammatically in the accompanying draw-

ing which is a vertical section through the machine.

A is a crushing hopper mounted on a base 55 A¹ and provided on its interior with a crushing lining A² the whole being mounted upon a foundation A³. A⁴ is a lower spider secured to the base and in this instance integral with the base of the crusher and adapted to carry the central shaft A⁵ which is secured to it and supported at its upper end by the upper spider A⁶ which is integral with the feed hopper A⁷ secured 60 to the crushing hopper A by the bolts A⁸.

B is a driving shaft upon which is mounted the belt pulley B¹ adapted to be driven by any suitable source of power not here shown. B² is a miter pinion on the shaft 70 B rotating in the oil pocket B³. It is in mesh with the miter gear B⁴ on the eccentric sleeve B⁵ which in turn is mounted for rotation upon the fixed central shaft A⁵ and is supported at its lower end upon the thrust 75 bearing B⁶.

C is a crushing head floating upon the eccentric sleeve B⁵ and in rotatable relation therewith. It is adjustably supported upon the ring C¹ by the adjusting screws C². This 80 ring C¹ is slidably supported on a bearing ring C³ provided with a packing washer C⁴ and having inclined oil and dust scraping edges as indicated. This bearing ring C³ is supported on the spider A⁴ and forms with 85 the ring C⁴ and the cylindrical extension C⁵ extending downwardly from the crushing head the upper boundary of an oil chamber in which most of the working parts are contained. This bearing plate C³ is held against 90 rotation on the spider and the walls of the oil chamber by means of pins C⁶. C⁷ is a resistant crushing shell preferably removable and made of manganese or similar durable material. It may or may not be corrugated 95 or folded. If it is removable on the crushing head as indicated it will be held in position thereupon by means of a holding bolt C⁸ engaging lugs C⁹ on the shell and drawn up by means of nuts C¹⁰ engaging shells C¹¹ 100 on the head. Under some circumstances this shell could be made integral with the crushing head by merely chilling the outer surface of the casting. Under ordinary circumstances, however, on high duty work 105 the manganese shell is preferable because it

lends itself more readily to renewal. If the manganese shell is dispensed with the crushing head is cast solid so that its outer shape is the same as that of the manganese shell.

5 D is a main lubricating supply pipe leading from a pump not here shown through one arm of the spider A⁶ into a passage D¹. This passage communicates with an annular ring D² about the upper end of the central 70 shaft. A radial passage D³ communicates at one end with the grooves D² at the other end with the central passage D⁴ which in turn communicates by means of radial passage D⁵ with an annular groove D⁶ in the 75 central portion of the fixed shaft. Oil forced through this system finally comes out into the groove D⁶ and moves up and down the central shaft lubricating the bearing of the eccentric on the shaft. D⁷ is a 80 passage through the eccentric always in register with the groove D⁶ whereby the bearing between the eccentric and the crushing head may always be lubricated. Any oil which passes up on the inside of the eccentric 85 will pass over the top and down to the chamber D⁸ formed between the packing ring D⁹ and the top of the crushing head. This packing ring D⁹ slidably engages a packing surface D¹⁰ on the upper portion 90 of the crushing head so as to make a substantially oil tight joint. The pressure is exerted upon this packing ring to assist in the oil tightness of this joint by means of the screw D¹¹ which completes a firm seating 95 of the packing ring on the upper end of the crushing head. The oil which passes down both outside and inside the eccentric sleeve 100 passes finally into the oil chamber at the base of the sleeve. The oil inside the sleeve 105 passes out and lubricates the thrust bearing supporting the eccentric. All the oil joins to lubricate the miter gear and pinion and then runs off through the pipe D¹² to the reservoir D¹³.

45 The bearings E E¹ in which the driving shaft B rotates are oiled by an oil duct E² branching off from the pipe D discharging into the chamber E³ between the bearings. Thence the oil works both 110 ways, some of it in the oiling chamber B⁴ at the foot of the eccentric sleeve and also some of it in the chamber E⁵ where the miter pinion E⁶ on the shaft B drives the miter gear E⁷ on a pump shaft E⁸ whereby the 115 pump driving mechanism is kept lubricated. Thence the oil returns by means of the pipe E⁹ to the pipe D¹² and thence to the reservoir.

The use and operation of my invention are 120 as follows:—

The material to be crushed is fed into the crusher through the feed hopper from above and passes into the crushing hopper where it is crushed by the gyration of the crushing head. The crushed material as it be-

comes small enough falls out at the bottom through the aperture between the crushing head and the hopper walls. This aperture may be kept of uniform size as the crushing head or the crushing walls, wear, by raising 70 the crushing apron by means of the adjustable nuts provided for that purpose, or the same adjustment may be to provide a change in the size of product; making the aperture smaller will result in finer crushing and 75 making it larger will result in larger crushing, the material being allowed to pass from the machine as soon as it is of a size small enough to pass through the aperture.

The sleeve extending downwardly from the crushing head passes through the supporting ring as indicated and oil is kept in and dust is kept out by means of the packing between the sleeve and the ring whereby the crushing head is free to move up and 80 down when the adjusting screws are manipulated without exposing the eccentric sleeve and without making it possible for oil to escape from or dust enter into the oiling chamber.

I claim:—

1. A crushing machine comprising a hopper, a central shaft, an eccentric sleeve mounted for rotation thereon a crushing head floating on and in rotatable relation 95 with the eccentric, means for moving the head bodily on the eccentric to adjust the relation between the head and the hopper said means comprising a supporting ring removed from the sleeve on which the crushing head rides, a thrust bearing upon which it slidably rests and adjusting screws between it and the head.

2. A crushing machine comprising a hopper, a central shaft, an eccentric sleeve 105 mounted for rotation thereon a crushing head floating on and in rotatable relation with the eccentric, means for moving the head bodily on the eccentric to adjust the relation between the head and the hopper 110 said means comprising a supporting ring, a thrust bearing upon which it rests and adjusting screws between it and the head a sleeve extending downwardly from and integral with the head fitting closely into and 115 being in slidable engagement with said ring.

3. A crushing machine comprising a hopper, a central shaft, an eccentric sleeve mounted for rotation thereon, a crushing head floating on and in rotatable relation 120 with the eccentric, an oiling chamber, sleeve rotating means contained therein, a closure for the chamber the end of the sleeve being located within the chamber and a portion of the crushing head projecting into the 125 chamber.

4. A crushing machine comprising a hopper, a central shaft, an eccentric sleeve mounted for rotation thereon a crushing head floating on and in rotatable relation 130

with the eccentric, an oiling chamber, sleeve rotating means contained therein, a closure for the chamber, the end of the sleeve being located within the chamber and a portion 5 of the crushing head projecting into the chamber and means for maintaining said chamber closed independent of all normal adjustment and operating movement of the crushing head eccentric sleeve and the driving means.

5. A gyratory crushing machine comprising a hopper a fixed central shaft an eccentric sleeve surrounding the shaft means for driving the sleeve a crusher head surrounding the eccentric sleeve in direct engagement therewith and an annular ring mounted for gyration with the head, adjustable head supporting means interposed between the annular ring and the head.

10. 6. A crushing machine comprising a hopper, a central shaft, an eccentric sleeve mounted for rotation thereon a crushing head floating on and in rotatable relation with the eccentric, means independent of the 15 shaft and of the eccentric sleeve for adjustably supporting the crushing head, said means comprising adjusting screws supported on an annular ring mounted for gyration with the head.

15. 7. A crushing machine comprising a hopper, a central shaft, an eccentric sleeve mounted for rotation thereon a crushing head floating on and in rotatable relation with the eccentric, means independent of the 20 shaft and of the eccentric sleeve for adjustably supporting the crushing head said means comprising adjusting screws supported on an annular ring mounted for gyration with the head, and a thrust bearing 25

40 adapted to support the annular ring.

8. The combination with a gyratory crushing head for crushing machines and the like of a central shaft within the head an eccentric sleeve mounted for rotation 45 about the shaft and within the head, means for rotating the sleeve, an oil chamber in which such means the lower end of the sleeve and the lower end of the crushing head are all contained packing means for maintaining such chamber constantly closed and an oil closure at the upper end of the crushing head containing the upper end of the sleeve the upper end of the crushing head and a portion of the central shaft.

55. 9. In a crushing machine comprising a hopper a central shaft and means for supporting it, an eccentric sleeve mounted for rotation thereon, a crushing head floating directly on and in rotatable adjustable relation with the eccentric, an oil chamber about the lower end of the shaft, inclosing the lower end of the eccentric sleeve, a ring adapted to support the crushing head, said ring closing the top of the oil chamber, the

lower edge of the crushing head adapted to 65 penetrate the oil chamber.

10. In a crushing machine comprising a hopper a central shaft and means for supporting it, an eccentric sleeve mounted for rotation thereon, a crushing head floating 70 directly on and in rotatable adjustable relation with the eccentric, an oil chamber about the lower end of the shaft, inclosing the lower end of the eccentric sleeve, a ring adapted to support the crushing head, said 75 ring closing the top of the oil chamber, the lower edge of the crushing head adapted to adjustably penetrate the oil chamber.

11. In a crushing machine comprising a hopper a central shaft and means for supporting it, an eccentric sleeve mounted for rotation thereon, a crushing head rotatably and adjustably mounted on the eccentric, an oil chamber about the lower end of the shaft, 80 inclosing the lower end of the eccentric sleeve, driving means for said eccentric inclosed within the oil chamber, a ring adapted to support the crushing head, in part closing the top of the chamber, a thrust bearing between such ring and the chamber wall, 90 the crushing head having a depending flange of uniform diameter, said flange adapted to penetrate the top of the oil chamber.

12. In a crushing machine comprising a hopper a central shaft and means for supporting it, an eccentric sleeve mounted for rotation thereon, a crushing head rotatably and adjustably mounted on the eccentric, an oil chamber about the lower end of the shaft, 95 inclosing the lower end of the eccentric sleeve, a ring adapted to support the crushing head, in part closing the top of the chamber, thrust bearing between such ring and the chamber wall, the crushing head having a depending flange of uniform diameter, 100 said flange adapted adjustably to penetrate the top of the oil chamber.

13. In a crushing machine comprising a hopper a central shaft and means for supporting it, an eccentric sleeve mounted for rotation thereon, a crushing head rotatably and adjustably mounted on the eccentric, an oil chamber about the lower end of the shaft, 110 inclosing the lower end of the eccentric sleeve driving means for said eccentric inclosed within the oil chamber, a ring adapted to support the crushing head, in part closing the top of the chamber, a thrust bearing between such ring and the chamber wall, the crushing head having a depending 115 flange of uniform diameter, said flange adapted to penetrate the top of the oil chamber, an oil chamber about the upper end of the shaft, adapted to contain the upper end of the eccentric sleeve, an oil closure about 120 the upper end of the eccentric sleeve, an oil closure about the upper end of the shaft, adapted to contain the upper end of the eccentric sleeve, an oil closure about 125 said oil chamber engaging the top of the crushing head and adjustable therewith.

14. In a crushing machine comprising a

hopper a central shaft and means for supporting it, an eccentric sleeve mounted for rotation thereon, a crushing head rotatably and adjustably mounted on the eccentric, an oil chamber about the lower end of the shaft, inclosing the lower end of the eccentric sleeve, driving means for said eccentric inclosed within the oil chamber, a ring adapted to support the crushing head, in part closing the top of the chamber, a thrust bearing between such ring and the chamber wall, the crushing head having a depending flange of uniform diameter, said flange adapted to penetrate the top of the oil chamber, an oil chamber about the upper end of the shaft, adapted to contain the upper end of the eccentric sleeve, an oil closure about said oil chamber engaging the top of the crushing head and adjustable therewith and in telescopic engagement with the roof of said oil chamber.

15. In a crushing machine comprising a hopper a central shaft, means for supporting it, a crushing head mounted on the shaft, an oil chamber about the lower end of the shaft inclosing the lower end of the crushing head, a ring adapted to support the crushing head, said ring closing the top of said oil chamber.

20. 16. In a crushing machine comprising a hopper a central shaft, means for supporting it, a crushing head mounted on the shaft, an oil chamber about the lower end of the shaft inclosing the lower end of the crushing head, a ring adapted to support the crushing head, said ring closing the top of said oil chamber, the lower edge of the crushing head adapted to penetrate the oil chamber.

25. 17. In a crushing machine comprising a hopper a central shaft, means for supporting it, a crushing head mounted on the shaft, an oil chamber about the lower end of the shaft inclosing the lower end of the crushing head, a ring adapted to support the crushing head, said ring inclosing a part of the chamber, a thrust bearing between such

ring and the chamber wall, a crushing head having a depending flange adapted to penetrate the top of the oil chamber.

50

18. In a crushing machine comprising a hopper a central shaft, means for supporting it, a crushing head mounted on the shaft, an oil chamber about the lower end of the shaft inclosing the lower end of the crushing head, a ring adapted to support the crushing head, said ring inclosing a part of the chamber, a thrust bearing between such ring and the chamber wall, a crushing head having a depending flange adapted adjustably to penetrate the top of the oil chamber.

55

19. In a crushing machine having a hopper a central shaft and means for supporting it, a crushing head rotatably and adjustably mounted, an oil chamber about the upper end of the shaft, and an oil closure about said oil chamber engaging the top of the crushing head and adjustable therewith.

60

20. In a crushing machine a hopper a central shaft and means for supporting it, a crushing head rotatably and adjustably mounted thereon, an oil chamber about the upper end of the shaft, an oil closure about said oil chamber engaging the top of the crushing head and the roof of the oil chamber and adjustable with the crushing head.

75

21. In a crushing machine a hopper a central shaft and means for supporting it, a crushing head rotatably and adjustably mounted thereon, an oil chamber about the upper end of the shaft, an oil closure about said oil chamber engaging the top of the crushing head and the roof of the oil chamber and adjustable with the crushing head with means for preventing the opening of such oil chamber by such adjustment.

80

In testimony whereof I affix my signature, in the presence of two witnesses, this 9th day of November, 1917.

EUGENE L. SANBORN.
